UNITED STATES PATENT OFFICE.

LLOYD FOWLER, OF SOUTH BRITAIN, CONNECTICUT.

VALVE-UNSEATING CLIP FOR TIRE-VALVES.

1,240,040.

Specification of Letters Patent. Patented Sept. 11, 1917.

Application filed June 22, 1917. Serial No. 176,334.

To all whom it may concern:

Be it known that I, LLOYD FOWLER, a citizen of the United States, residing at South Britain, in the county of New Haven, State of Connecticut, have invented a new and useful Valve-Unseating Clip for Tire-Valves; and I do hereby declare the following to be a full, clear, and exact description of the invention, such as will enable others skilled in the art to which it appertains to make and use the same.

The present invention relates to a spring clip, and has for its object to provide a device of this character which embodies novel features of construction whereby it can be advantageously used for different purposes, such as for holding a tire valve open while folding an inner tube, as a paper clasp, clothes pin, ox bow pin, display hanger, or the like.

Further objects of the invention are to provide a spring clip of this character which can be inexpensively formed of sheet metal, which will securely grip and engage the object to which it is applied, which can be easily manipulated, and which will enable an inner tire tube to be completely collapsed and tightly folded without the necessity of unscrewing the check valve from the tire valve casing, or without necessitating the services of a second person to hold the check valve open while folding the tire.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:—

Figure 1 is a plan view of the blank from which the valve unseating clip constructed in accordance with the invention is formed.

Fig. 2 is a perspective view of the valve unseating clip.

Fig. 3 is a vertical sectional view through the same, showing the manner of applying the clip to a tire valve casing.

Corresponding and like parts are referred to in the following description and indicated in all the views of the drawings by the same reference characters.

The clip proper is designed to be formed from a rectangular blank A of sheet ma-

terial, said blank being provided with longitudinal slits 1 which extend from opposite ends thereof and have a parallel relation to each other and to the edges of the blank, said slits being also substantially equidistant from each other and from the edges of the blank. The central or body portion 2 of the blank is thus provided upon each side thereof with an integral wing 3, said wings 35 being formed with rearward extensions 4 which initially extend parallel to the body portion 2 of the blank, being separated therefrom by the slits 1. These wings 3 project from opposite sides of the body portion 70 2 at opposite ends thereof, and after bending the said body portion 2 into the form of an arch or bow, the wings 3 are folded rearwardly against the ends of the body portion, fitting closely against the same to 75 provide gripping jaws formed of a double thickness of sheet material. The extensions 4 then extend rearwardly from the back of the arched body portion 2 and form finger pieces which can be grasped when manipulating the clip. The ends of the arched body portion 2 form opposed spring jaws for gripping an object inserted between the same, and it will be obvious that when applying the clip in position or removing it 80 therefrom, these jaws can be spread apart by pressing the finger pieces 4 together and flexing the back of the arched spring strip 2. The extensions 4 are preferably returned so that they serve not only as finger pieces 85 for manipulating the clip, but also as a means for hanging the clip from a suitable support. If preferred, however, the ends of the extensions or finger pieces 4 might be cut off.

The gripping edges of the jaws are shown as concaved so as to conform to the exterior curvature of a standard tire valve casing, thereby enabling them to engage the threads of the tire valve casing to hold the clip securely in position. The edges of the outer thicknesses or wings 3 may be returned around the concave edges of the jaws, as indicated at 5, thereby holding the two thicknesses securely together, and also providing 105 reinforced jaws for engagement with the tire valve casing.

A stem 6 projects from the back of the arched spring strip 2 and carries a small concave head or handle 7 which is adapted 110 to enter the mouth of the tire valve casing and engage the inner valve element to unseat

the same and hold it in an open position. This provides for the escape of air from the inner tire tube, and enables the tire tube to be completely collapsed and tightly folded 5 without unscrewing and removing the inner valve element, or without the necessity of utilizing the services of a second person to hold the inner valve in an open position while folding the tube. This stem 6 is pref- 10 erably detachably connected to the back of the arched spring strip 2, and for this purpose the rear end thereof may be provided with a head 8 which is provided in the sides thereof with slits 9 adapted to engage and 15 interlock with the contracted end of a key-hole slot 10 in the strip 2. This head 8 can be inserted into the enlarged end of the key-hole slot 10 and then moved laterally to bring the slits 9 into engagement with the 20 reduced end of the said key-hole slot, there- by locking the stem 6 and head 7 firmly in position, although they can be removed by the reverse of the above operation. The sheet metal of the arched strip 2 may be 25 provided at points adjacent the key-hole slot 10 with slightly raised portions or cor- rugations 11 for assistance in holding the head 8 of the stem 6 at the reduced end of the key-hole slot 10, the said head 8 spring- 30 ing over the raised portions 11 as it is in- serted in position or removed therefrom.

When the stem 6 and head 7 are in position, the clip can be readily applied to the exterior of a tire valve casing with the con- 35 cave head 7 projecting into the mouth of the casing and engaging the inner valve element to unseat it and hold it in an open position, thereby enabling the inner tube to

be completely collapsed and folded without difficulty. When the head 6 and stem 7 are removed or omitted, the clip can be used for many different purposes, such as a paper 40 clasp, clothes pin, ox bow pin, display hanger, or the like.

Having thus described the invention, what 45 I claim as new and desire to secure by Letters Patent, is:—

1. A clip of the character described in- 50 cluding a bowed spring strip terminating at its ends in opposed jaws adapted to grip a tire valve casing or the like, integral wings folded over the jaws from the sides thereof to reinforce the same, and rearward exten- 55 sions projecting from the wings and extending beyond the back of the bowed spring strip to provide finger pieces for flexing the spring strip to move the jaws apart.

2. A clip of the character described, in- 60 cluding a bowed spring strip terminating at its ends in opposed jaws adapted to grip a tire valve casing or the like, integral wings bent laterally over the jaws from the sides thereof and having edge portions thereof returned around the gripping portions of the jaws, and rearward extensions project- 65 ing from the wings and extending beyond the back of the bowed strip to provide op- posed finger pieces for flexing the bowed strip to move the jaws apart.

In testimony whereof I have signed my 70 name to this specification in the presence of two subscribing witnesses.

LLOYD FOWLER.
